CLAIM

The ornamental design for a truck rack, as shown and described.

DESCRIPTION

FIG. 1 is a front right perspective view of a truck rack showing my new design;

FIG. 2 is a right side elevational view thereof, the left side elevational view being a mirror image thereof;

FIG. 3 is a top plan view thereof;

FIG. 4 is a bottom plan view thereof;

FIG. 5 is a front elevational view thereof; and,

FIG. 6 is a back elevational view thereof.

The phantom lines in FIG. 1 are for illustrating a pickup truck in an environmental view of the track rack and form no part of the claimed design.

The truck rack is shown on an enlarged scale in FIGS. 2–6.
